FLANGING MACHINE

Alfred H. McCabe, Lawrence, Mass.; Lauretta M. McCabe executrix of said Alfred H. McCabe, deceased, assignor to Annie A. McCabe, Frederick C. McCabe, and Francis H. McCabe, a partnership doing business as McCabe Manufacturing Company, Lawrence, Mass.

Application August 24, 1942, Serial No. 456,104

8 Claims. (Cl. 153—16)

The present invention relates to flanging machines and more particularly to that type of machine designed for cold-flanging the curved edges of metal plates to form circular flanged ends or heads of boilers, tanks, etc., and constitutes an improvement on the flanging machine disclosed in the patent to Hugh McCabe, No. 1,006,861, dated October 24, 1911.

The machine of that patent operates to flange a circular disk or plate by subjecting successive small portions or sections of the marginal portion of the disk to a series of bending operations or steps of limited extent, whereby the material is gradually and progressively brought to the designed angular position to form the flange.

Formerly, it was the practice in making these flanged heads, or boiler ends, to make the bend of the flange of relatively short radius, i. e., three inches or less for heads up to eight feet in diameter. More recently a much longer radius of bend is employed, the A. S. M. E. (American Society of Mechanical Engineers) standard being a radius that is six per cent of the diameter of the flanged head. Thus, for a head eight feet in diameter the bend of the flange would be about a radius of approximately five and three-fourths inches. While the machine of the McCabe Patent No. 1,006,861 operated successfully to cold flange a disk or plate with the old, relatively short radius of bend, such a machine was unsatisfactory when used to form the present type of long radius bend, because the free marginal portion or edge of the flange, instead of being circular or cylindrical, had a wavy or undulating contour. These waves or undulations, it is believed, were caused by the excess of metal measured peripherally or laterally which results from the reduction in the diameter of such marginal portion as it was bent from its original extended to its final contracted position. For example, if a flanged head of eight-foot diameter were to be formed with the A. S. M. E. standard radius of bend, the peripheral or circumferential length of the outer margin of the bend would be reduced nearly twenty-one inches over the peripheral length of this same portion in the original work disk, or nearly twice the reduction if the older three inch radius bend had been used. Since all these flanges have a straight or cylindrical portion or band at their free margins, an even greater reduction in peripheral length than that specified would necessarily result, the amount depending upon the depth of the band.

It is the object of the present invention to adapt machines for cold flanging metal plates, such as

of the type disclosed in the prior McCabe patent, to operate successfully to form flanges with the present standard longer radius of bend by providing means whereby as the bending operation progresses, the peripheral length of the free marginal portion of the flange will be progressively shortened until when the flange has reached its final predetermined position, it will be substantially circular or cylindrical without undulation or distortion.

I have discovered that if in addition to the bending operation, the marginal portion of the work be subjected to a compressing operation while under stress, this undulation or wavy edge 15 of the flange will be avoided and a smooth circular flange from angle to edge will be produced.

The flange so formed, I have noted, has been substantially increased in thickness, to the greatest extent adjacent the edge, and progressively less inwardly therefrom. This increase, it is believed, represents the transfer of metal laterally from the side margins of the bent down portions towards the middle of such portions, as the width of such portions, particularly adjacent the periphery, is reduced.

Since only a small portion of the flange area is bent in each cycle of operation in the repeated series of operative steps in forming the flange, the amount of metal to be transferred in any 20 single bending and compressing operation is relatively slight and such transfer can be successfully accomplished without requiring the heating of the metal.

The present invention consists in the provision 35 in a cold flanging machine of the above general type, of means whereby each incremental portion of the flange is subjected to a compressing operation in addition to the bending and stressing operation, in order to reduce progressively 40 the width thereof, more particularly in the peripheral or edge portions of such portion, by increasing the thickness thereof. Preferably this is accomplished by providing an anvil or abutment member against which the incremental portions 45 of the flange are compressed by the bending element of the machine in its final movement in a bending stroke.

In the accompanying drawings which illustrate the present invention as applied to the machine 50 of the McCabe Patent No. 1,006,861, Fig. 1 is a side elevation of the machine with the parts in position to receive the work; Fig. 2 is a side elevation, partly in section, on an enlarged scale, showing the work and bending and compressing 55 mechanisms just as the bending and compressing

operations have been completed; Fig. 3 shows in perspective, on an enlarged scale, one of a series of removable anvil blocks which support the work during the compressing operation; Fig. 4 is another perspective of the lifting member carried by the bender block for lifting the anvils from inoperative to operative positions; Figs. 5, 6 and 7 showing different stages of operation of the machine, Fig. 5 showing the work and operative parts before any bending whatsoever has been produced in the marginal portion of the metal disk; Fig. 6 showing the position of the work and operative parts at the end of the first bending and compressing operation, and Fig. 7 showing the same at the end of the next to the last bending and compressing operation; and Fig. 8 is a horizontal section on line 8—8 of Fig. 7 showing the parts in horizontal section.

The machine shown in these drawings corresponds in its general features of construction with the machine of Patent No. 1,006,861, and it comprises means for supporting and clamping the sheet metal work, ordinarily a disk, with an extended free marginal portion to be turned or bent to form the flange, a bender for engaging and imparting a recurring series of limited bending movements to small portions of such margin, an oscillating support for the bender, and a pneumatic power cylinder with suitable control devices for actuating the support and the bender in its bending and return strokes.

Referring to Fig. 1, the work is supported upon the table or work support 1, which is arranged to be raised by the wedge 5 to press the work firmly against the top clamp plate 6. The wedge is actuated through the link 7, bell-crank lever 8 and rod 9 from the pneumatic cylinder 10 with manual control valve 11 whereby the compressed air may be admitted to either end of the cylinder to raise or lower the support 1.

The bender 2 is provided with an operating base plate 17 to engage a small, wedge-shaped portion of the unsupported margin of the work plate to impart thereto a bending movement of the desired limited extent. When operating upon the curved margin of a metal disk, the plate is concave on its operating face to give a slight curve or arc to the work, as hereinafter described. The bender is mounted upon a segmental carrier 19 supported for oscillatory movement in a segmental guideway in the frame of the machine and provided with a segmental actuating gear 24. This gear is engaged by the rack 25 extending from the pneumatic power cylinder 27 controlled through the hand valve 28. Actuation of the valve in one direction causes outward movement of the piston rod and rack, imparting clockwise movement to the segmental gear 24 and effecting the power stroke of the bender. Actuation of the valve in the opposite direction reverses the motion of these parts and causes the return or idle stroke of the bender.

After each operation of the bender on a short section of the marginal portion of the plate, the latter is unclamped, turned slightly to bring into position the adjacent unbent portion, again clamped and the bender again operated to produce the desired bending of the new portion. Thus successive adjacent portions are subjected to the operation of the bender until the entire marginal portion of the plate has been given its initial bend.

To effect the second series of bending operations to produce still further bending of the flange portion, the rack 25 is withdrawn from engage-

ment with the segmental gear 24 and then re-engaged in such position that the working stroke of the bender will be angularly advanced whereby an additional series of further bending movements will be imparted to the initially bent margin or flange.

When the second series of bending operations has been completed around the circumference of the plate, another adjustment of the rack will be made and another series of still further bending operations carried out, and so on, until the flange is brought to final position which is ordinarily at right angles to the plane of the plate or head, the plate 46 fixedly mounted upon the frame of the machine serving as a stop to limit the final bending movement and thus insure the correct angular position of the completed flange. The flange contacting face of this plate is slightly convex to cooperate with the concave face of the bender plate 17 and impart a slightly curved or arc shape to each flange portion operated upon so that the flange when completed will be cylindrical throughout its perimeter and not composed of a large number of flat or tangential surfaces.

It will be noted that in the McCabe patent drawings the curvature of the rounded upper corner of the table or work support about which the flange is bent is of relatively short radius, to produce the sharper bends in accordance with the then-prevailing practice.

It will also be noted that in the series of bending operations as practiced by this machine of the McCabe patent, the extent of each bending operation is determined solely by the extent of movement of the bender, there being no abutment or other stop to limit the bending movement of the flange, except in the final series, when in order to determine accurately the final position of the flange, a stop plate is employed.

In order to modify this machine and its mode of operation so that it can produce the flanges with the much longer radius of bends now required, without giving a scalloped or wavy margin or edge to the flanges, the table or work support 1 has been formed with a very much greater radius of curvature at its inner upper corner, and there have been provided anvil or abutment blocks against which each bent portion of the flange or margin is forcibly compressed to cause the cold flow of the material with resulting decrease in peripheral width of each section with a corresponding increase in thickness, particularly adjacent the edge.

These anvil or abutment blocks are preferably formed in a series with cooperating nesting surfaces, the entire series being employed for the first series of bending movement and one block being removed successively for each new series of steps.

It is also desirable that the abutment block or blocks shall move back and forth from inoperative to operative position so that they will not interfere with the positioning of the plate between successive operations of the bender.

As shown in Figs. 1 and 2, the anvil or abutment blocks 50, 52 and 54 are positioned against the abutment plate 46, all three blocks being in operation when the first step or series of bending operations are carried out. Fig. 1 shows these blocks in their lowered or inoperative position which they assume when a plate is to be inserted in the machine or to be repositioned for another bending operation. As the bender advances to make its bending stroke, these blocks are raised, as shown in Fig. 2, and in this position support

the margin or flange portion of the plate against the compression of the bender. Conversely, as the bender retracts, the blocks are lowered from their operative position, shown in Fig. 6, to their inoperative position, shown in Fig. 5.

The anvil blocks are of general wedge shape with front convex and back concave faces, as shown in Fig. 8, and are positioned with the thickened or wider ends downward, with the back concave face of what may be termed the first wedge, 50, engaging the front convex face of the second wedge 52, the back face of which in turn engages the front face of the third wedge 54, the back concave face of which engages the convex face of the fixed plate 46. The lower back corner of the wedge 50, it will be observed, is recessed, as at 56, to receive the shoulder 58 on the second wedge, which in turn is supported by the shoulder 60 on the third wedge 54, which, when the bender is retracted, rests upon the arcuate guideway of the machine. By means of the tension springs 62, one on each side of the machine, secured at one end to one or another of the pins 64 extending from each side of the blocks 50, 52 and 54, and at the other end to the pins 55 on the frame of the machine, the blocks are held securely in proper position yet are free to be raised and lowered as required.

The mechanism for raising and lowering the blocks from inoperative to operative position, comprises the curved shoe or cam 70 secured to the lower end of the bender 2 by countersunk bolts 72, which cam in the downward or operative stroke of the bender engages the bottom face of the third block 54 and through its camming or wedging action raises such block and with it the first and second blocks supported thereby from the position shown in Fig. 5 to that shown in Fig. 6. The bottom or wider end portions of the first and second blocks 50 and 52 are positioned above the guideway so that the cam may pass beneath the same and out of contact therewith, the blocks remaining in their lowermost position until the cam or shoe engages and lifts the third block which in turn raises blocks 52 and 50. The plate 46 is cut away at 74 to permit the passage of the cam or shoe 70 in the latter portion of its operative stroke.

In the drawings the machine is shown as provided with a set of three anvil blocks and with this arrangement the flange will be bent from its initial to its final position in four series or steps of bending operations, the first one being performed with all three blocks in place, the second step with two blocks in position, the third step with only one block in the machine, and the fourth step with all three blocks removed and compression taking place against the plate 46. These numbers of blocks and of steps of operation have been found satisfactory with common weights or thicknesses of plate and with the usual depth of flange. Where, however, a heavier than normal plate is employed or a deeper than the usual flange is to be formed, it may be desirable to provide a greater number of thinner blocks than three and to operate with a greater number of steps than four, as above described.

In the operation of the machine and before the work has been inserted, the parts are in the position shown in Fig. 1, with the wedge 5 retracted and the clamping plate 1 lowered. The bender is in its top position with the cam or shoe 70 withdrawn from beneath the anvil block 54, and the three blocks in their lowered position. The work is then inserted in the machine with its free edge extended beyond the clamping mem-

bers the distance required to make the flange of the desired depth. The immediate parts are then in the position shown in Fig. 5, with the work unclamped.

By means of the controlling hand valve for the cylinder 10, the operator causes actuation of the wedge block 5 to raise the bottom clamp 1 and to clamp the work securely against the upper clamp 6. Then, by proper manipulation of the control valve 28, he causes the rack 25 to be actuated and through it the segmental gear 24 and the bender 2. The bender plate 17 is quickly brought into engagement with the free margin of the work and in its continued movement bends the same downwardly about the rounded end of the work support 1. Meanwhile the shoe or cam 70 is passing beneath the anvil blocks 50 and 52 to engage block 54 and raise all three blocks to the position shown in Figs. 2 and 6, the blocks reaching their upper or operative position just before the portion of the plate being operated upon is brought into contact with the first block. Continued motion of the bender brings the parts into the position shown in Figs. 2 and 6, with the bent portion of the work in contact with the face of block 50. This completes, as it were, the bending operation, but the operator continues to supply compressed air to the power cylinder 27, increasing the pressure on the work between the bender plate and the anvil block 50 until it is sufficient to cause the cold flow of metal from the sides of the work inwardly toward the middle, particularly at the periphery where the width is greater, thereby increasing the thickness of the bent and compressed work portion, more especially adjacent the margin.

On completion of the compressing stroke the operator, by proper manipulation of the control valve 28, causes the return movement of the bender to its original position during which time the anvil blocks are lowered. The clamping member or work support 1 is then released by proper manipulation of the valve 11 for the clamping cylinder 10, and the work, then being unclamped and free, is turned slightly to bring the next adjacent portion into proper position for bending and compression. The above described operation is repeated a sufficient number of times until the entire margin of the plate has been given its preliminary set or bend.

To adjust the machine for the second series of steps of bending and compressing operations, the rack 25 is adjusted upon the segmental gear 24 to lower the stroke of the bender, both with respect to its initial and to its final positions, so that in its power stroke it will impart further bending to the work. Before this is done block 54 will be removed, the compression springs 62 being detached from the pins 64 on the sides of the block and applied to the pins on block 52. The work will now be clamped and the bender again actuated as before, with alternate re-positionings of the work and actuations of the bender until the second step or series has been completed.

The third and fourth steps or series follow in the same manner, the latter series being performed with all of the blocks removed and the work being compressed against the fixed plate 46.

On completion of the final step when the work is unclamped and removed from the machine, it will be found that a flange has been formed with a true circular free margin, without waves or undulations, but of substantially greater thickness, particularly adjacent the margin, than before the bending operation was begun.

While the machine shown in the drawings has been described as forming a right angled flange in four bending and compression steps, it is obvious that any desired angle up to 90° can be obtained by the use of the proper number of properly shaped anvil blocks and proper operation of the bender actuating devices.

Only one form or shape of table or work support has been shown in the drawings, but it is to be understood that tables of different shapes may be supplied to provide for varying radii of curvatures for various diameters of the work in accordance with the A. S. M. E. standard.

While the present invention has been shown as embodied in a particular construction of machine and parts thereof, it is to be understood that in its broader aspects it is not limited thereto but may be embodied in other constructions and arrangements within the scope of the appended claims.

Having thus described the invention, what is claimed is:

1. A flanging machine for cold flanging the curved edge of a metal plate having, in combination, supporting and clamping devices for holding the plate with an unsupported margin, a bender, a series of movable interlocking abutment members movable as a unit between operative and inoperative positions, and mechanism for actuating the bender and the abutment members, including means engaging one of the series of abutment members to actuate the series.

2. A flanging machine for cold flanging the curved edge of a metal plate having, in combination, supporting and clamping devices for holding the plate with an unsupported margin, a bender, an oscillating support for the same, a movable abutment member, means carried by the oscillating support for causing the abutment member to move between inoperative and operative positions, and mechanism for oscillating the support to cause the bender to bend successive portions of the plate and to compress the same to reduce the peripheral length of the curved edge thereof, the support moving the abutment up into operative position when the support is oscillated in the direction to render the bender operative, and into inoperative position when the support is oscillated in the opposite direction.

3. A flanging machine for cold flanging the curved edge of a metal plate having, in combination, supporting and clamping devices for holding the plate with an unsupported margin, a bender, a series of removable interlocking supplementary abutment members adapted as such members are successively removed one at a time, to provide a series of abutment faces of progressively varying angularity, and mechanism for actuating the bender to bend and compress a portion of the margin of the plate on successive actuations of the bender to bring such portion to the desired final angle of bend.

4. A flanging machine for cold flanging the edge of a metal plate having, in combination, supporting and clamping devices for holding the plate with an unsupported margin, a bender, a fixed abutment plate and a series of separately and successively removable cooperating wedge-shaped abutment blocks adapted to be supported by the fixed plate against the thrust of the bender to provide an abutment face of progressively variable angularity as the blocks are successively removed, and mechanism for actuating the bender

to bend successive portions of the margin of the plate against each abutment face in succession to impart the desired final angle of bend to such portions.

5. A flanging machine for cold flanging the curved edge of a metal plate having, in combination, a support for the plate, a clamp to hold the plate securely on the support with an unsupported margin, a bender arranged to move in an arcuate path in engagement with a portion of such margin adjacent its periphery, mechanism for actuating the bender in a successive series of arcuate strokes to cause it to bend such portion in increasing degree with each successive series of strokes, and abutment means comprising a plurality of abutment blocks, said blocks being shaped to provide an abutment face of variable angularity against which such portion will be compressed by the bender on a bending stroke, and means for removably mounting the blocks in position to support against the pressure of the bender the portion of the work being bent, with the angularity of the abutment face corresponding to the stroke of the bender.
6. A flanging machine for cold flanging the curved edge of a metal plate having, in combination, a support for the plate, a clamp to hold the plate securely on the support with an unsupported margin, a bender arranged to move in an arcuate path in engagement with a portion of such margin adjacent its periphery, mechanism for actuating the bender in a successive series of arcuate strokes to cause it to bend such portion in increasing degree with each successive series of strokes, an abutment comprising a plurality of abutment blocks to provide an abutment face against which such portion will be compressed by the bender on a bending stroke, and means for supporting a variable number of said blocks in contact one with another to provide an abutment face of variable angularity.

7. A flanging machine for cold flanging the edge of a metal plate having, in combination, supporting and clamping devices for holding the plate with an unsupported margin, a bender movable in an arcuate path to bend and compress a portion of such margin in a successive series of operative strokes, an abutment member movable transversely of the path of the bender into and out of position to support against the pressure of the bender the portion being bent and compressed, and actuating mechanism for the bender and abutment to cause the bender to make a successive series of operative and return strokes and the abutment member to move into and out of supporting position when the bender makes its operative and return strokes, respectively.

8. A flanging machine for cold flanging the edge of a metal plate having, in combination, supporting and clamping devices for holding the plate with an unsupported margin, a bender arranged to engage one face of the work, means comprising a series of cooperating separately removable abutment members for presenting an abutment face of progressively variable angularity as such members are successively removed, and mechanism for actuating the bender in a curved variable path to bend progressively successive portions of the margin of the plate and to compress the same against an abutment face by a successive series of operative strokes, corresponding to the angularity of the abutment face.

ALFRED H. McCABE.
